CLAIM

The ornamental design for mobile power source, as shown and described.

DESCRIPTION

FIG. 1 is a perspective view of a mobile power source according to our new design;

FIG. 2 is a front elevational view of the mobile power source of FIG. 1;

FIG. 3 is a rear elevational view of mobile power source of FIG. 1;

FIG. 4 is a top plan view of the mobile power source of FIG. 1;

FIG. 5 is a bottom view of the mobile power source of FIG. 1;

FIG. 6 is a left hand side elevational view of the mobile power source of FIG. 1; and,

FIG. 7 is a right hand side elevational view of the mobile power source of FIG. 1.

The broken line showing of the environment is for illustrative purposes only and forms no part of the claimed design.
